UNITED STATES PATENT OFFICE.

THEODOR RICHTER, OF SPANDAU, GERMANY.

FRAME.

Application filed February 13, 1924. Serial No. 692,619.

To all whom it may concern:

Be it known that I, THEODOR RICHTER, a citizen of the German Republic, residing at Spandau, Germany, have invented certain new and useful Improvements in Frames, of which the following is a specification.

Frames for mowing and binding machines, forming the subject of the invention and having four main members assembled in pairs, are characterized according to this invention in that said members are each formed of a single piece pressed to U-shape and as far as possible of uniform strength throughout its length in respect to the stresses to be carried by it, said members being placed on edge, and whereof the members lying parallel to the working direction of the machine are provided with pressed out bearing portions for the main driving shaft of the machine mechanism, while their ends engage exactly into the cross sectional form of the other members. The provision of members of uniform strength throughout their length in respect to the stresses to be carried thereby, is secured by making said members relatively wide at their intermediate portions and tapering them substantially, uniformly toward their ends.

The invention further provides that the member carrying the pull when the machine is working is formed integrally with the draw-eye, and is so arranged that the pull comes on substantially in the plane of this member.

By the new construction the number of parts and their connections is reduced to a minimum, whereby in combination with the cross-sectional form of the members and the use of one and the same material of construction the frame possesses extraordinary strength and light weight, while the low cost and high speed of production for the frames of these machines have not previously been approached. It therefore precisely meets the requirements of the frames of mowing and binding machines, namely, to provide a strong base for the machine but with the least possible weight in all the construction elements and yet so that no stress on the machine in use shall effect a permanent strain.

The usual construction of frames, such as in bridge building, only partially fulfills these requirements in that the main members

are built up of several separate parts of different kinds of material secured together by rivets, bolts and the like. These connections produce the inaccuracies customary in the construction of clumsy machines, and affect to great disadvantage the stiffness and length of serviceable life of frames on which are thrown heavy and varied demands.

By this invention deficiencies of the kind mentioned are obviated on account of the single-piece main members. This integral construction also renders possible a very economical mass production of the frames, since for binders of all sizes with the same form frames may be produced whereof the ends of the longitudinal members at least may be given the size of section suited to any case in question by suitably trimming up the length, so as to fit very accurately the adjoining channel section. The known construction on the other hand requires a specially produced frame for each machine.

It is also important that the bearing portions pressed out in the members lying in the direction of the machine when working enable a firm and vibration-free seating of the main driving shaft, so that a reliable driving of the various usual mechanisms such as the cutting, binding and conveying devices of the machine from this shaft is assured.

The accompanying drawing shows an example of frame according to the invention, Figure 1 showing the frame in perspective; Fig. 2 a detail of construction to an enlarged scale, and Fig. 3 the frame as seen from the side remote from the blades, the wheels being indicated in the working position of the machine by dot and dash lines.

The parallel main members *a*, *a'* are each pressed in a single piece to a U-shaped cross-section and placed on edge. They lie transverse to the working direction of the machine and constitute the two longitudinal members in relation to the shape of the frame. In their inwardly facing channels they take the ends of the cross members *c* and *d* arranged at right angles thereto and in the working direction of the machine, these also being pressed in one piece from sheet metal.

Moreover all the members are of regular form and dimensioned so that the strength at any section is substantially proportional to the stresses ordinarily incurred there in

practice. The frame may thus be described as a body of uniform strength. The cross members *b*, *c* terminate in rectangularly formed enlargements *d* so that a connection 5 of the longitudinal and cross members of the frame which will rigidly resist forces in all directions can be effected without the help of separate gussets or the like.

The main wheel *l* shown in dot and dash 10 lines in Fig. 3 is carried by cross members *b*, *c* and in order to take the bearings of the main shaft *h* which is driven from the main wheel *l* on rotation thereof, bearing portions 15 *e* are pressed into the cross members *b*, *c*, the liners or bearing proper *i* being inserted directly into said bearing portions. Also 20 the draw-eye *f* which carries the pull when the machine is working is formed integrally with the inner cross member *c*, so that the entire frame including the most important 25 appendages is formed of only four main construction members, and has a simplicity and strength not hitherto achieved. If desired the number of parts may be further 30 reduced: for example by making the parts *a*, *b* and *a'* integral the frame will consist of only two parts.

An essential feature of my invention consists in making the main parts of the frame 35 in the manner herein described, so that the above-mentioned advantages of strength and rigidity, saving of material, reduction of weight as well as simplicity of construction will result. Instead of the flanges *g* shown 40 in Fig. 1, for instance, also elevated or depressed surfaces may be pressed into the members.

I claim:

1. As an article of manufacture a frame 45 for a mowing and binding machine consisting of four main members of pressed metal shaped to a channel or U form in cross section and made relatively wide at intermediate portions thereof and being substantially uniformly tapered toward their ends to 50 thereby render them of uniform strength throughout their length, without excess weight, with respect to the loads to be carried, all of said members having their web portions vertically and their flange portions, 55 horizontally disposed, two of said members being materially longer than the others and being disposed transversely of the line of travel of the frame when in use, with their open sides inward and the other two of said members being disposed adjacent each other and toward the same end of the first 60

said members snugly interfitting into the open sides of the first named members.

2. As an article of manufacture a frame 65 for a mowing and binding machine consisting of four main members of pressed metal shaped to a channel or U form in cross section and made relatively wide at intermediate portions thereof and being substantially uniformly tapered toward their ends to thereby render them of uniform strength 70 throughout their length, without excess weight, with respect to the loads to be carried, all of said members having their web portions vertically and their flange portions, 75 horizontally disposed, two of said members being materially longer than the others and being disposed transversely of the line of travel of the frame when in use with their open sides inward and the other two of said members being disposed adjacent each other and toward the same end of the first named members the flanges at the ends of the last 80 named members being materially widened and said ends being of box-like, closed formation, said ends being snugly interfitting and secured by suitable fastenings in the 85 open sides of the first named members.

3. As an article of manufacture a frame 90 for a mowing and binding machine consisting of four main members of pressed metal shaped to a channel or U form in cross section and made relatively wide at intermediate portions thereof and being substantially uniformly tapered toward their ends to thereby render them of uniform strength 95 throughout their length without excess weight, with respect to the loads to be carried, all of said members having their web portions vertically and their flange portions, horizontally disposed, two of said members being materially longer than the others and being disposed transversely of the line of travel of the frame when in use with their open sides inward and the other two of said members being disposed adjacent each other and toward the same end of the first 100 named members the interfitting ends of the last named members being widened and of box-like, closed formation, said ends being snugly interfitting and secured in the open sides of the first named members, the remaining end of one of the last named members being pressed into the form of an integral open draw eye which embraces the first named member, perpendicular thereto.

In testimony whereof I have hereto affixed my signature.

THEODOR RICHTER.
